CLOSURE FOR MILK BOTTLES AND THE LIKE

Kempton Clark, Little Compton, R. I., assignor to American Seal-Kap Corporation of Delaware, Long Island City, N. Y., a corporation of Delaware

Application December 12, 1935, Serial No. 54,022

5 Claims. (Cl. 215—38)

This invention relates to closures for containers, more particularly milk bottles and the like, and has for a particular object to provide a closure which effectively seals the bottle and which gives evidence of any tampering.

A further object is to provide such a construction which permits ready unsealing and opening of the bottle when this is desired, the bottle mouth being then entirely free from sealing material or foreign matter which could contaminate the contents of the bottle when being poured out.

A further object is to provide means for sealing to the bottle a bottle cap having a skirted pouring lip housing so that the skirt is sealed to the bottle neck below it, reinforcing the skirt against flaring and preventing the entry of foreign matter between it and the bottle.

These and other desirable objects are obtained by applying to the capped bottle a strip of sealing material overlapping the skirt and the bottle mouth or neck adjacent thereto, and conforming to both, the end portions of the strip being sealed together when the strip has been passed entirely around the circumference of the cap and bottle.

For a more complete understanding of this invention, reference may be had to the accompanying drawing in which

Figure 1 is a somewhat diagrammatic view of a milk bottle to which a cover-all cap has been applied and showing the application thereto of the sealing strip.

Figure 2 is a side elevation of the sealed bottle.

Referring to the drawing, at 1 is indicated a glass bottle of the type used to contain milk or cream. After this container has been filled it is closed by a cap 2, provided with a downwardly turned skirt portion 3 which engages about the outside of the bottle adjacent to its top. This cap, as shown, is of the well known cover-all type and may be made in accordance with the Baum Patent No. 1,668,349 granted May 1, 1928. Such caps are commonly formed of a paper composition suitably moisture proofed, being formed up from a paper disk with its edges folded together and compacted to form the skirt 3. If desired, it may have a central reinforcing disk as shown, for example, in the patent to Baum, No. 1,619,283, granted March 1, 1927.

The skirt extends downwardly about the outer face of the bottle to such an extent as to bring its lower edge which is thick enough to form a substantial shoulder adjacent to a portion 4 of the bottle neck which progressively is of reduced diameter for a distance from the top of the

bottle. This skirt 3 prevents the entry of foreign matter into contact with the pouring lip of the bottle, so that when the cap has been removed, the pouring lip is clean and sanitary. The cap having been applied to the filled bottle, the cap is then sealed to the bottle in such a manner that any tampering with the cap is easily detected and in such a manner as to prevent the entry of foreign matter in between the skirt and the bottle.

This means comprises a strip 5 of thin film-like material of considerable extensibility so that when it is wound under tension about the top of the bottle, overlapping the skirt and adjacent parts of the bottle, it conforms automatically thereto including the shoulder at the lower edge of the skirt, and when the ends of the strip have been brought together into overlapping relation as shown at 6 and there secured together, the cap is securely sealed to the bottle. This winding is shown as accomplished by hand. This sealing film, beside being quite extensible so as to conform to the contours of the parts about which it is wound, should also have other characteristics. It should be non-porous and moisture proof in order that it shall not take into itself any undesirable foreign matter which might by any chance contaminate the contents of the bottle after removal of the cap. It should also be of material which will not adhere strongly to the bottle so that it may be readily removed therefrom and be antifouling so as to not leave deposit which might carry foreign matter to the next filling and thereby cause possible contamination. It should also be sealable to itself so that it may be secured in position readily. There are several materials which can be used for this purpose, some of which, however, are more advantageous than others in that they have the desired characteristics to a more complete extent. Among materials which may be used for the purpose may be mentioned thin membranes or films of gutta percha, rubber, particularly of the type commonly used for insulating wire provided with a rubber adhesive which will facilitate self-sealing of the overlapped ends of the material together; rubber compositions such as those containing rubber hydrohalides as disclosed, for example, in the Calvert Patent No. 1,989,632 granted January 29, 1935, and such hydrohalides in combination with wax such as paraffin or the like. Such compositions, more particularly of chlorinated rubber, are marketed under various trade names, one of which is "Pliofilm." A material particularly suitable is known

in the trade as "Parafilm" and is a composition of rubber and wax, this material being manufactured by the Marathon Paper Mills Company of Rothschild, Wisconsin. This material is described in United States Letters Patent No. 2,054,112 and No. 2,054,115 granted to Abrams et al. September 15, 1936, and is particularly suitable since it will stretch up to about 100%, seals on itself under pressure, either with or without heat, and is waterproof. It does not adhere strongly to either the bottle or the bottle cap, but the adhesion to itself is sufficient to hold it in place when wound under tension as heretofore described.

15 A milk bottle is under particularly favorable conditions for the avoidance of adhesion of materials such as described which are somewhat heat sensitive and which are moisture proof, in that the bottle as it passes from the filling machine is cold and commonly wet over that portion where the sealing film will be applied, so that under such conditions it affords a surface repellent to thermoplastic adhesive agents of the film material which are of utility for effecting self-sealing of the overlapped ends of the film together. Such film materials are so thin that they afford little resistance to turning of the cap when it is desired to open the bottle, but such turning of the cap so destroys their continuity 30 that it is very evident when the bottle has been opened.

Furthermore, the film being wound under tension about the skirt of the cap retains this skirt in closed condition against the bottle, insuring against any tendency to flare due to rough handling or, since it is waterproof, to the entry of moisture into the cap material should the cap not be thoroughly waterproof. Due to the lack of adhesion of the film to both the bottle and to the cap, the sealing of the overlapping ends of the strip to each other constitutes the major portion of the securing of the strip in sealing position. These various materials may be procured in different colors so that besides effecting 45 a seal impervious to moisture and providing evidence of tampering should the cap have been removed, they may produce a highly ornamental effect.

From the foregoing description of the method 50 of this invention and certain embodiments thereof, it should be evident to those skilled in the art that various changes and modifications might be made without departing from the spirit or scope of this invention as defined by the appended 55 claims.

I claim:

1. In combination, a container having a closure cap provided with a skirt engaging the outside of the container below its top, the cap skirt being thick enough to form a substantial shoulder at 60 the lower edge thereof, and a strip of sealing film surrounding and contacting said container and in overlapping relation to said skirt and with its ends in overlapping relation to each other, said film being formed of extensible material consisting of a thermoplastic composition which is adapted to be rendered sufficiently soft and tacky by heat to be sealable onto itself and is not sufficiently adherent to either the container or cap

to be secured thereto by adhesion, said strip being held under sufficient tension to be conformed to the contour of the container and cap and the shoulder formed by the lower edge of the cap skirt, and being secured substantially solely by 5 the sealing of its ends together.

2. In combination, a container having a closure cap provided with a skirt engaging the outside of the container below its top, a strip of sealing film surrounding and contacting said container and in overlapping relation to said skirt and with its ends in overlapping relation to each other, said film being formed of extensible material consisting of a thermoplastic composition which is heat sealable onto itself and is not sufficiently adherent to either the container or cap 10 to be secured thereto by adhesion, said strip being held under sufficient tension to be conformed to the contour of the container and cap, and being secured substantially solely by the sealing of its 15 ends together.

3. In combination, a container having a closure cap provided with a skirt engaging the outside of the container below its top, a strip of sealing film surrounding and contacting said container and in overlapping relation to said skirt and with its ends in overlapping relation to each other, said film being formed of extensible material consisting of a wax-rubber composition which is heat sealable onto itself and is not 20 sufficiently adherent to either the container or cap to be secured thereto by adhesion, said strip being held under sufficient tension to be conformed to the contour of the container and cap, and being secured substantially solely by the sealing of its 25 ends together.

4. In combination, a container having a closure cap provided with a skirt engaging the outside of the container below its top, the cap skirt being thick enough to form a substantial shoulder at the lower edge thereof, and a strip of sealing film surrounding and contacting said container and in overlapping relation to said skirt and with its ends in overlapping relation to each other, said film being formed of extensible material consisting of a rubber composition which 40 is sealable onto itself and is not sufficiently adherent to either the container or cap to be secured thereto by adhesion, said strip being held under sufficient tension to be conformed to the contour of the container and cap and the shoulder 45 formed by the lower edge of the cap skirt, and being secured substantially solely by the sealing of its ends together.

5. In combination, a container having a closure cap provided with a skirt engaging the outside of the container below its top, a strip of sealing film surrounding and contacting said container and in overlapping relation to said skirt and with its ends in overlapping relation to each other, said film being formed of extensible material consisting of a rubber composition which is sealable onto itself and is not sufficiently adherent to either the container or cap to be secured thereto by adhesion, said strip being held under sufficient tension to be conformed to the contour of the container and cap, and being secured substantially solely by the sealing of its ends together.

KEMPTON CLARK.
